US00D961676S

(12) **United States Design Patent** (10) **Patent No.:** **US D961,676 S**
Jameson et al. (45) **Date of Patent:** **** Aug. 23, 2022**

(54) **LABEL SHEET WITH FEED EDGE ASSEMBLY**

(71) Applicant: **CCL Label, Inc.**, Framingham, MA (US)

(72) Inventors: **Alan Jameson**, West Covina, CA (US); **Eric Cushing**, Riverside, CA (US); **Le-Hoa Hong**, Monterey Park, CA (US); **Sriram Venkatasanthanam**, Chino Hills, CA (US); **Adam Bratter**, Newport Coast, CA (US); **Heba Armand**, Placentia, CA (US); **Ana Trinh**, Rowland Heights, CA (US)

(73) Assignee: **CCL LABEL, INC.**, Framingham, MA (US)

(**) Term: **15 Years**

(21) Appl. No.: **29/752,224**

(22) Filed: **Sep. 25, 2020**

Related U.S. Application Data

(62) Division of application No. 29/676,819, filed on Jan. 15, 2019, now Pat. No. Des. 900,926, which is a division of application No. 29/584,761, filed on Nov. 17, 2016, now Pat. No. Des. 841,087.

(57) **CLAIM**

The ornamental design for a label sheet with a feed edge assembly, as shown and described.

DESCRIPTION

FIG. 1 is a front view of a first embodiment of a label sheet with a feed edge assembly showing our new design; FIG. 2 is a front view of an second embodiment of a label sheet with a feed edge assembly showing our new design; and,

FIG. 3 is a back view of a third embodiment of a label sheet with a feed edge assembly showing our new design.

1 Claim, 3 Drawing Sheets
